UNITED STATES PATENT OFFICE.

LOUIS GOLDBERG, OF CHICAGO, ILLINOIS.

DESIGN FOR AN ELECTRIC-LIGHTING FIXTURE.

56,869.

Specification for Design.

Patented Jan. 4, 1921.

Application filed August 5, 1920. Serial No. 401,527. Term of patent 3½ years.

To all whom it may concern:

Be it known that I, LOUIS GOLDBERG, a citizen of the United States, residing at Chicago, in the county of Cook and State of Illinois, have invented a new, original, and ornamental Design for Electric-Lighting Fixtures, of which the following is a specification, reference being had to the accompanying drawing, forming part thereof.

The figure is a front view of an electric lighting fixture, showing my new design.

I claim:

The ornamental design for an electric lighting fixture, as shown.

In witness whereof I affix my signature.

LOUIS GOLDBERG.
